(57) **CLAIM**

The ornamental design for a “radial feed facing head for boring bar,” as shown and described.

DESCRIPTION

FIG. 1 is a perspective view of the radial feed facing head for boring bar showing our design;

FIG. 2 is a front elevational view thereof;

FIG. 3 is a top elevational view thereof;

FIG. 4 is a bottom side elevational view thereof;

FIG. 5 is a right side elevational view thereof;

FIG. 6 is a left elevational view thereof; and,

FIG. 7 is a rear elevational view.
